UNITED STATES PATENT OFFICE.

CHARLES J. SEITER, OF NEW YORK, N. Y.

DESIGN FOR A LAMP-BODY.

SPECIFICATION forming part of Design No. 28,306, dated February 22, 1898.

Application filed November 18, 1897. Serial No. 659,042. Term of patent 7 years.

To all whom it may concern:

Be it known that I, CHARLES J. SEITER, a citizen of the United States, residing at New York city, in the county and State of New York, have invented and produced a new and original Design for Lamp-Bodies, of which the following is a specification, reference being had to the accompanying drawing, forming a part thereof, which represents a front elevation of a lamp-body embodying the features of the design.

The leading feature of the design consists in a body A, which represents a flower, sundry of the leaves B whereof are brought together, forming a hollow globe, and other

leaves C are dropped from the globular group of leaves, presenting two distinct formations, an upper globular section and a lower draping section.

A minor feature of the design consists in a standard D, which appears as a support for the body.

I claim—

The design for a lamp-body, herein shown and described.

CHARLES J. SEITER.
